N. W. TAPLIN.

FURNACE.

APPLICATION FILED FEB. 26, 1921.

Patented Dec. 12, 1922.

Inventor:

Neal W. Tajiri

by Cyrus W. Rice

This Attorney

UNITED STATES PATENT OFFICE.

NEAL W. TAPLIN, OF GRAND RAPIDS, MICHIGAN.

FURNACE.

Application filed February 26, 1921. Serial No. 447,938.

To all whom it may concern:

Be it known that I, NEAL W. TAPLIN, a citizen of the United States, residing at Grand Rapids, in the county of Kent and 5 State of Michigan, have invented new and useful Improvements in Furnaces, of which the following is a specification.

The present invention relates to furnaces; and its object is to provide an improved furnace whereby a high degree of combustion of the fuel therein may be attained; and further, to provide a furnace having an air-supplying channel in one member thereof, such member and channel being so formed 15 that said member shall be securely supported on the furnace's lower member, and in such manner as shall prevent deforming by the extreme heat developed in the furnace; and further, to provide simple and efficient means 20 for supplying air to and through said channel for the purpose of effecting a high degree of combustion.

These and any other objects hereinafter appearing are attained by, and the invention 25 finds preferable embodiment in, the structure hereinafter particularly described and illustrated by the accompanying drawings, in which:—

Figure 1 is a sectional view of portions of 30 a furnace taken on vertical planes corresponding to line 1—1 of Figure 2;

Figure 2 is a sectional view of the same taken on a horizontal plane corresponding to line 2—2 of Figure 1;

Figure 3 is a sectional view of a part of 35 the same taken on a vertical plane corresponding to line 3—3 of Figure 2;

Figure 4 is a view in perspective of the upper one of a pair of plates forming air-supplying conduits leading to the interior 40 of the furnace;

Figure 5 is a like view of the lower one of 45 said plates; and

Figure 6 is a sectional view of certain 50 parts, somewhat enlarged and showing a modified construction.

In the embodiment of the invention chosen for illustration by the drawings and for detailed description in the body of this specification, the furnace comprises a hollow lower member 1 constituting the "fire pot" of the furnace, and a hollow upper member 2 constituting the "combustion chamber" (or a

part thereof) of the furnace. The upper member 2 has in its lower edge-portion an air-supplying channel 3, curved or arcuate in a horizontal plane conformably with the contour of the furnace, and having inner and outer curved walls 4, 5 formed or cast integral with said member 2 itself. These walls, thus spaced apart to form the channel 3 between them, each rest at their bottom edges on and are supported by the upper edge-portion 6 of the lower member 1. This lower member's said upper edge-portion is curved in a horizontal plane in registration with the lower edge-portion of the upper member 2 and has a curved or arcuate groove 7 registering with the lower edge of the outer wall 5 of the air-channel 3, and a similar curved or arcuate rabbet 8 registering with the lower edge of the inner wall 4 of said air-channel, said outer wall being seated in the groove and said inner wall being seated in the rabbet. It will be seen that the upper member 2 is thus securely supported on the lower member 1 at points spaced apart in radial directions; and also, that inasmuch as the outer wall 5 is seated in the groove 7 and the inner wall 4 is seated in the rabbet 8, the outer wall is held against lateral movement in either direction and the inner wall against such movement outwardly. Thus the walls of the air-channel 3 and the members 1 and 2 themselves are so interrelatively held as to be prevented from distortion or deformation caused by extreme degrees of heat.

The inner wall 4 of the air-supplying channel 3 has air-passages 9 therethrough and spaced apart as shown whereby air passes to the interior of the furnace to promote combustion. This air-supplying channel 3 is open at both ends 10, 11 and air is supplied thereto through air-conduits 12, 13 respectively. These are conveniently formed by two horizontally disposed plates 14, 15, spaced apart and located adjacent the door-opening or fuel-supply opening 16 of the furnace and at the bottom thereof, said opening having the door or closure 17 having a hollow-portion 18. One of these plates, as the upper plate 14, has a rib 19 adjacent its inner edge projecting downwardly into contact with the lower plate 15, and has also a second rib 20 extending forwardly from the

rib 19 and likewise projecting downwardly into contact with the lower plate, to form the pair of air-supplying conduits 12, 13, separated by the rib 20, so that part of the air received from outside the furnace is directed through conduit 13 and through the opening 21 at the inner ends of the contacting ribs 22, 23 carried by the upper and lower plates respectively, and into the right-hand open end 11 of the air-channel 3, while the other part of the air supplied to the furnace passes through the opening 24 at the inner ends of the other contacting ribs 25, 26 carried by the upper and lower plates respectively and into the left-hand open end 10 of said air-channel. It will be seen that the air is thus admitted to the interior of the furnace at spaced apart points or passages 9 instead of being all admitted at one point in the circumference of the combustion chamber. To more perfectly effect this end, the cross-sectional area of the passages 9, especially those nearer the open ends of the air-channel 3 are so related to the cross-sectional area of the air-passage 3 itself as to force a portion of the air therein to seek outlet through other passages 9 spaced further and further from the channel's open ends.

30 The lower plate 15 is provided with a downwardly extending retaining rib 30 seated in the groove 7, and the upper plate 14 resting on the upper edge of the ribs 31 of the lower plate is secured thereto by bolts 35 (not shown) passing through orifices 32, 33 in the plates respectively.

In Figure 6 is shown a modified construction in which the air passages 9¹ are open at their bottoms.

40 The invention being intended to be pointed out in the claims, is not to be limited to or by details of construction of the particular embodiment thereof illustrated by the drawings or hereinbefore described.

45 I claim:

1. In a furnace; a hollow lower member constituting the furnace's fire pot and having a curved groove in its upper edge-portion; a hollow upper member having an air-supplying channel in its lower edge-portion with outer and inner walls formed integral with said upper member, one of said walls being seated in said groove and the other being supported on the lower member's upper edge-portion and said inner wall having spaced air passages therethrough leading to the interior of the furnace.

2. In a furnace; a hollow upper member having an air-supplying channel in its lower edge-portion with outer and inner curved walls formed integral with said upper member, said inner wall having spaced air passages therethrough leading to the interior of the furnace; a hollow lower member constituting the furnace's fire pot and having in

its upper edge-portion depressions adapted to receive and hold against lateral movement in at least one direction said inner and outer walls of said air-supplying channel.

3. In a furnace; a hollow lower member 70 constituting the furnace's fire pot; a hollow upper member having an air-supplying channel in its lower edge-portion with outer and inner walls formed integral with said upper member and severally supported on the lower member's upper edge-portion and said inner wall having spaced air passages therethrough leading to the interior of the furnace.

4. In a furnace; a hollow lower member 80 constituting the furnace's fire pot and having a curved groove in its upper edge-portion; a hollow upper member having an air-supplying channel in its lower edge-portion with outer and inner walls and being open 85 at its ends, one of said walls being seated in said groove and the other being supported on the lower member's upper edge-portion and said inner wall having spaced air passages therethrough leading to the interior 90 of the furnace; a pair of horizontally disposed connected plates spaced apart to form a pair of air-supplying conduits leading to the open ends respectively of said air-supplying channel, one of said plates having a retaining rib seated in said groove.

5. In a furnace; a hollow lower member constituting the furnace's fire pot and having a curved groove in its upper edge-portion; a hollow upper member having an air-supplying channel in its lower edge-portion with outer and inner walls and being open 100 at its ends, one of said walls being seated in said groove and the other being supported on the lower member's upper edge-portion and said inner wall having spaced air passages therethrough leading to the interior of the furnace; a pair of horizontally disposed spaced-apart plates, one of said plates 105 having a rib adjacent its inner edge projecting toward the other plate and a second rib extending forwardly and rearwardly and projecting toward said other plate to form a pair of air-supplying conduits leading to the open ends respectively of the air-supplying channel.

6. In a furnace; a hollow lower member having a curved groove and a horizontally-extending ledge in its upper edge portion; a hollow upper member having an air-supplying channel in its lower edge-portion with outer and inner walls formed integral with said upper member, the outer wall being seated in said groove and the inner wall being supported on said ledge and having spaced air passages therethrough leading to the interior of the furnace.

7. In a furnace; a hollow lower member having in its upper edge portion a curved groove and a horizontally-extending ledge 136

with an upward extension; a hollow upper member having an air-supplying channel in its lower edge-portion with outer and inner walls formed integral with said upper member, the outer wall being seated in said groove and the inner wall being supported on said ledge and held against outward

movement by said extension and having spaced air passages therethrough leading to the interior of the furnace.

In testimony whereof I have hereunto set my hand at Grand Rapids, Michigan, this 16th day of February, 1921.

NEAL W. TAPLIN.
